(57) **CLAIM**

I claim the ornamental design for the firearm grip, as shown and described.

DESCRIPTION

FIG. 1 is a front perspective view of the firearm grip; FIG. 2 is a front elevation view of the firearm grip of FIG. 1;

FIG. 3 is a rear elevation view of the firearm grip of FIG. 1;

FIG. 4 is a right side view of the firearm grip of FIG. 1;

FIG. 5 is a left side view of the firearm grip of FIG. 1;

FIG. 6 is a top view of the firearm grip of FIG. 1

FIG. 7 is a bottom view of the firearm grip of FIG. 1; and,

FIG. 8 is a rear perspective view of the firearm grip of FIG. 1.

The broken lines in the drawings are used to illustrate unclaimed portions of the invention and form no part of the claimed design.

1 Claim, 6 Drawing Sheets
